INTERCHANGEABLE BUILDING CONSTRUCTION UNIT

Peter J. Minck, Indianapolis, Ind.

Application January 8, 1941, Serial No. 373,526

4 Claims. (CL. 72—16)

This invention relates to building construction and particularly to a concrete unit to be pre-formed and to be set up on the job to form selectively the wall and the floor support of a building. It is a primary object of the invention to provide an exceedingly simple unit that may be readily molded and delivered to the job without further work on the unit to have the unit erected and bolted one to another to form the building structure.

A further primary object of the invention is to incorporate in the building unit means for anchoring lath or the like on the insides of the units to support plastering or the like. A still further important object of the invention is to form the individual structural units in such manner that they may serve as conduits for warm or cold air as may be desired for heating and air conditioning of the building.

Other objects and advantages of the invention, such as the simple means for uniting one unit with another, application of reenforcing means, and the general labor saving found in employing the units, will become more apparent to those versed in the art in the following description of one particular form of the invention as illustrated in the accompanying drawings, in which

Fig. 1 is a view in inside elevation of a plurality of the structural units embodying the invention and assembled in a wall;

Fig. 2, a view in transverse section on the line 2—2 in Fig. 1;

Fig. 3, a view in side elevation of a single unit mounted on a typical foundation wall indicated in section;

Fig. 4, a detail in transverse section of a corner construction assembly embodying the individual units;

Fig. 5, a detail in partial section through a foundation wall showing the supporting arrangement thereon of the units when used both in a wall and for floor support; and

Fig. 6, a view in transverse section through one of the units showing insulation means applied.

Like characters of reference indicate like parts in the several views in the drawings.

Referring to the drawings, a number of identical units, generally designated by the numeral 10, is formed, each to have a major transverse wall section 11 from which, on the same side thereof, 50 are turned from each marginal portion legs 12 and 13 to terminate in a common plane, whereby the unit 10 has a generally widened U-shape in cross-section, as indicated in Figs. 2 and 4. The distance from the outer face of the wall section 55

11 to the terminal edge of each leg 13 determines the thickness of the wall formed upon assembling the units one at the side of another.

Across one end of each unit is formed an end wall 14 having its outer surface in the same plane as are the outer surfaces of each of the legs 12 and 13. Each unit 10 is provided with a plurality of spaced apart holes 15 through the legs 12 and 13 and within these holes are positioned resilient collars or sleeves 16 made out of any suitable material in the nature of rubber or synthetic rubber.

Then each unit 10 is further provided, particularly when it is to be used for wall construction, with tacking strips 17 and 18, one against each of the inner faces of the legs 12 and 13. Preferably, although not necessarily so, crossbars 19 are provided to retain the strips 17 and 18 in spaced apart relation and in contact with the inner faces of the legs 12 and 13. These strips 17 and 18 and the crossbars 19 may be made out of any suitable material to receive nails or other securing means to support metal or wood lath thereacross. Wood may be used for these elements 17, 18 and 19.

To form a wall, one unit 10 is set up on the top side of a foundation wall 20. Preferably the foundation wall 20 is provided with an outer upwardly projecting aligning rib 21 against which the outer face of the wall section 11 may be abutted with the lower ends of the legs 12 and 13 resting on the top face of the foundation 20. The unit 10 is positioned to have the cross wall 14 at its upper end as indicated in Fig. 1.

The next unit 10 is similarly positioned on the foundation 20 to have its leg 13 in abutting contact throughout its height with the leg 12 of the first positioned unit 10. Bolts 22 are passed through the sleeves 16 in both the abutting legs 12 and 13, the bolts being passed through the strips 17 and 18 and there secured by nuts screw-threadedly engaging the bolts. The use of the sleeves 16 take care of any slight misalignment that may exist between the two adjacent units 10 and that also may exist in the spacing of the holes in one leg in reference to those in another leg. Furthermore, it is to be noted that the bolts do not bear at any place in direct contact with the concrete of which the units are formed so that danger of cracking or breaking the concrete is thus avoided. The use of the strips 17 and 18 (the strips being themselves resilient in nature) extends the pressure produced by the bolts over a considerable area reaching beyond the immediate area of the bolt head.

One unit after another is thus aligned on the foundation 20 until the desired length of wall is secured. The upper ends of the assembled line of units 10 receive a rafter plate 23 or the like, to be secured to the units by any suitable means, such as by bolts 24 passing through the plate 23 and down through the cross wall 14. This plate 23, of course, further aids in maintaining the alignment of the units 10 along the wall.

In reference to the strips 17 and 18 and the spacing bars 19, these strips and their spacing bars may be made up in units and then inserted into position between the respective legs 12 and 13 at the time the concrete units 10 are being erected so that not only are the finished strips preformed in assembled relation but also the concrete members 10 are preformed, whereby there is no carpenter work or skilled labor required in the actual formation on the erecting job of any parts of the units.

As above indicated, each unit 10 is molded or cast out of concrete. Where expense is not prohibitive, these units may be made out of other suitable material, such as the synthetic resins that may be likewise molded. In any event, there is preferably incorporated in each unit 10 suitable reenforcing means, particularly through the legs 12 and 13. In the present form, a continuous reenforcing rod or bar 25 is used to extend longitudinally through each leg 12 and 13, integrally across through the wall 14, and integrally across in exposed relation between the lower ends of those legs 12 and 13. As herein indicated, this reenforcing bar 25 in each unit 10 is spaced outwardly in the legs beyond the bolt holes 15.

After the wall has been formed as above indicated, with the lower ends of the respective units 10 resting on the foundation wall 20, additional concrete 26 is preferably employed to be flowed into the lower end of each unit 10 to embed the initially exposed cross part of the reenforcing rod 25. As indicated in the drawings, Figs. 1-3, this concrete 26 may be carried around downwardly on the inside of the foundation 20. Further, to provide a water-tight seal between abutting units 10, a groove 27 is molded longitudinally in each side of the unit just inside of the outer face thereof. Then when the two adjacent units are bolted together, the groove 27 in one unit will match with the groove 27 in the adjacent unit and thereby provide a continuous passageway from top to bottom between the assembled units. This passageway may then be filled with any suitable sealing material, preferably of a plastic nature.

The unit 10, as above described, may not only be used in multiple to form a building wall but they may also be used to form a supporting structure for a floor, as indicated in Figs. 4 and 5. For this purpose, the foundation 20 is provided with a suitable shoulder 28 which may be at or below the top of the foundation, herein shown as being below. The units 10 have their ends resting on this shoulder 28 to have either the legs turned downwardly or upwardly, herein shown as having the legs turned upwardly with the wall section 11 undermost. Then after the floor area has been filled in with these units, one alongside the other and suitably secured together, as above indicated, by bolts 22, the floor may be built thereover such as by placing expanded metal lath across the upper sides of the legs of the units and concrete or like material poured thereover and finished to a floor level.

Where the space between the legs of each unit 10 is to be used as a conduit for air flow, the legs are turned upwardly, as indicated in Figs. 4 and 5, and as will be noted, this space in the floor units 10 will open in part at least into like spaces in the upright units 10. Of course the units 10 will have to be turned end for end to prevent the cross end walls 14 from interrupting the flow from the floor to the wall unit. The units 10, when used in the floor, may be disposed to have the end walls 14 alternately spaced, one at one end and one at the other end on the respective supporting foundation walls. On the other hand, where the unit 10 is to conduct air in both longitudinal directions in the floor, the end wall 14 may be omitted in those particular units. When the units 10 are employed in the floor construction, then it is not necessary to use the fill-in concrete 26 in the lower ends of the upright units 10, particularly if the horizontal units are to be used as air conduits.

As indicated in Fig. 4, the use of the units 10, constructed as above indicated, permits a very substantial corner construction since the bolts 22 in the two end units at the corner may be carried through a vertically positioned angle iron 29 and then a finish corner strip 30 employed to fill in between those two adjacent units 10.

Reference is made particularly to Figs. 3, 4 and 6 wherein insulating means is illustrated. Where it is desired to insulate the wall of the building employing the units of the invention, the strips 17 and 18 are reduced in width and have a wall 31 secured to their rear edges to leave a space between that wall and the inner face of the wall 11 of the unit. Suitable insulating material 32, which may be mineral wool, such as rock wool, glass wool, or any non-deteriorating material of like nature, is poured or packed in this space between the wall 31 and the wall 11. In this manner the unit is completely insulated against transmission of heat from one side to the other of the unit and moreover moisture transmission through the unit wall, particularly where it is made out of concrete and the like, is prevented. It is conceivable, of course, that the insulating material 32 may be omitted and the wall 31 itself be made out of insulating material so that an air space is left for insulation in place of employing the insulating material 32.

While the invention has been discussed in more or less minute detail, it is obvious that structural changes may be employed without departing from the spirit of the invention, such, for example, as in the particular means for aligning the units on the foundation and there securing them, and it is, therefore, desired that the invention not be limited to that precise form beyond the limitations as may be imposed by the following claims.

60 I claim:

1. A building construction member comprising a pre-formed, narrow, trough-like unit made of concrete generally U-shaped in transverse section to form a wall with a pair of equal length legs extending in the same direction one from each side edge of the wall, each leg having a plurality of spaced apart holes therethrough, insulating means comprising a pair of fibrous side strips and a wall of insulating material secured to and spacing apart said strips to have each strip in substantial contact with the inner opposing faces of said legs, said strips having holes therethrough aligned axially with said leg holes, and bolt-like means extending through said strips and said leg holes, whereby a plurality of said

members may be placed side by side, one leg of one member in contact with a leg of another member and joined together resiliently.

2. A building construction member comprising a pre-formed, narrow, trough-like unit generally U-shaped in transverse section to form a wall with a pair of equal length legs extending in the same direction one from each side edge of the wall, each leg having a plurality of spaced apart holes therethrough, and a resilient collar in each of the holes, whereby a plurality of said members may be placed side by side to be joined one to another by bolts through said collars in adjacent legs, a pair of resilient side strips and a wall secured to and spacing apart said strips to have each strip in substantial contact with the inner opposing faces of said legs, said strips having holes therethrough aligned axially with said collars, and bolt-like means extending through said strips and said collars, said strips being less in width than said faces to space said secured wall a distance from said unit wall to leave a conduit therebetween, and insulating material compressively secured in said conduit by pressure of said secured wall thereagainst.

3. A building construction member comprising a pre-formed, narrow, trough-like unit generally U-shaped in transverse section to form a wall with a pair of equal length legs extending in the same direction one from each side edge of the wall, each leg having a plurality of spaced apart holes therethrough, and a resilient collar in each of the holes, whereby a plurality of said members may be placed side by side to be joined one to another by bolts through said collars in adjacent legs, a pair of resilient side strips and a wall

5 of relatively non-heat conducting material secured to and spacing apart said strips to have each strip in substantial contact with the inner opposing faces of said legs, said strips having holes therethrough aligned axially with said collars, and bolt-like means extending through said strips and said collars, said strips being less in width than said faces to space said secured wall a distance from said unit wall to leave a conduit therebetween, and insulating material compressively secured in said conduit by pressure of said secured wall thereagainst.

4. A building construction member comprising a pre-formed, narrow, trough-like unit generally U-shaped in transverse section to form a wall with a pair of equal length legs extending in the same direction one from each side edge of the wall, each leg having a plurality of spaced apart holes therethrough, and a resilient collar in each of the holes, whereby a plurality of said members may be placed side by side to be joined one to another by bolts through the said collars in adjacent legs, a pair of nail penetrable and retaining side strips and a wall secured to and spacing apart said strips to have each strip in substantial contact with the inner opposing faces of said legs, said strips having holes therethrough aligned axially with said collars, and bolt-like means extending through said strips and said collars, said secured wall being formed of insulating material, a cross-wall between said legs at the top end of said unit, and said secured wall extending upwardly to said cross-wall.

PETER J. MINCK.
